UNITED STATES PATENT OFFICE.

CHRISTOPHER CLARKE, OF NORTHAMPTON, MASSACHUSETTS.

CAR-COUPING.

SPECIFICATION forming part of Letters Patent No. 286,999, dated October 23, 1883.

Application filed February 16, 1883. (No model.)

To all whom it may concern:

Be it known that I, CHRISTOPHER CLARKE, of Northampton, in the county of Hampshire and State of Massachusetts, have invented certain new and useful Improvements in Car-Couplings, of which the following, taken in connection with the accompanying drawings, is a specification.

The object of my present invention is to provide a car-coupling that may be adjusted to different heights, in order to adapt it to couple with cars having their coupling-sockets at different heights from the track.

It is a well-known fact that railway-cars are made after a variety of patterns, and that their draw-bars or coupling-sockets are at different heights from the track; and in the case of freight-cars this difference in construction is a great source of trouble in making up trains in which cars from several different roads are used, as is now a common practice.

My invention consists in a draw-bar and coupling-head made in two parts, and adapted to be moved vertically one upon the other, and mechanism for making such adjustment of the coupling-head both from the side and top of the car, which will be best understood by reference to the description of the drawings, and to the claims to be hereinafter given.

Figure 1 of the drawings is an end elevation of a box freight-car having my improvements applied thereto. Fig. 2 is a partial side elevation of the same. Fig. 3 is a partial vertical section on line xx in Fig. 1, drawn to an enlarged scale. Fig. 4 is a section on line yy on Fig. 3, drawn to the same scale; and Fig. 5 is a partial end elevation of a platform freight-car with my improvement applied thereto.

A is the car-body of ordinary construction. B is the truck-frame, C the wheels, and D the axle.

E is the draw-bar, the rear portion of which is constructed and applied to the car-body in the usual manner; but instead of having the socket to receive the coupling-link formed in its outer end in the usual way, it has formed in its outer end a vertical T-shaped groove or slot, a , to which is fitted so as to slide vertically therein the coupling-head F, provided with the link-receiving socket b , and the re-

movable coupling-pin c , of ordinary construction.

G is a screw mounted at its upper end in a bearing in the ear d , formed upon the upper part of the outer portion of the draw-bar E, 55 its threaded lower portion working in a nut or threaded hole in the coupling-head F, in such a manner that by revolving said screw the head F may be raised or lowered relative to the center line of the draw-bar at will. The 60 upper end of the screw G is connected by means of the link H and two universal or gimbal joints, I I, to the lower end of the shaft J, mounted in bearings $e e'$ upon the front end 65 of the car-body, and provided at its upper end with the hand-wheel K, by means of which it may be revolved by the brakeman upon the top of the car to raise or lower the coupling-head F to the desired position to engage with the coupling of another car. The gimbal or 70 universal joints I I and the link H are necessary upon a box-car, in order to allow for the yielding and expansion of the draw-bar spring, and at the same time have the long shaft J mounted in fixed bearings. In order that the 75 same adjustment may be made by a brakeman or other person standing upon the ground, I mount a horizontal shaft, L, in bearings $f f$ on the front end of the car-body, and mount upon its outer end the hand-wheel M, and upon its 80 inner end the bevel-gear wheel N, which engages with the bevel-gear wheel O, fitted to the shaft J, so as to revolve therewith, and mounted by its hub in the bearing e' , so that it cannot be moved endwise with the shaft J, which has 85 a slight vertical movement imparted to it as the link H is moved from a perpendicular position to a position at a greater or less angle to a perpendicular by the endwise movements of the draw-bar E.

In applying my invention to a platform-car, as illustrated in Fig. 5, the link H, gimbal-joints I I, and shaft J are dispensed with, the screw-shaft G being extended upward some distance above the ear d of the draw-bar E, 95 and has firmly secured thereon, just above the ear d , the bevel-gear wheel O, and at its upper end the hand-wheel K, as shown. The horizontal shaft L, in this case, is mounted at its outer end in the swiveling bearing P, mount- 100

ed in the stand P', in such a manner that it may be moved about a vertical axis, and at its other end in the stand or bearing Q, mounted upon and supported by the screw-shaft G and the draw-bar E, as shown in Fig. 5.

The operation of my invention will be readily understood by a careful examination of the drawings, in connection with the description herein given, without further explanation.

10 A dovetailed slide may be formed in the front end of the draw-bar, instead of the T-shaped groove or slot a, and the rear end of the coupling-head F be made to fit the same without affecting the principles of my invention.

15 What I claim as new, and desire to secure by Letters Patent of the United States, is—

1. In a car-coupling, a draw-bar and a coupling-head made separate and connected together by a vertically-sliding coupling-joint, 20 in combination with a screw for raising and lowering said coupling-head and means for operating said screw both from the top and side of the car, substantially as and for the purposes described.

25 2. The combination of the draw-bar E, the draw-head F, connected to said draw-bar E by

a sliding joint or bearing, a vertical screw arranged to work in said head as a nut, and arranged to be operated from the top of the car, the bevel-gear wheels N and O, and the horizontal shaft L, extending to the side of the car, and provided at its outer end with a hand wheel or crank, whereby the draw-head can be adjusted to different heights, either from the top of the car or from the side, substantially as described.

3. The combination of a draw-bar and draw-head, made separate, and connected by a sliding joint or bearing, a screw working in said head as a nut, and adapted to raise or lower 40 said head, and means of operating said screw from the side of the car, substantially as described.

In testimony whereof I have signed my name to this specification, in the presence of two sub- 45 scribing witnesses, on this 13th day of February, A. D. 1883.

CHRISTOPHER CLARKE.
